UNITED STATES PATENT OFFICE.

JAMES P. JOHNSON, OF KENSAL, NORTH DAKOTA.

WRENCH.

No. 901,174.

Specification of Letters Patent.

Patented Oct. 13, 1908.

Application filed October 26, 1905. Serial No. 284,501.

To all whom it may concern:

Be it known that I, JAMES P. JOHNSON, a citizen of the United States, residing at Kensal, in the county of Stutsman and State 5 of North Dakota, have invented a new and useful Wrench, of which the following is a specification.

This invention relates to wrenches and has for an object to provide a wrench embodying new and improved features of durability, reliability, convenience and efficiency.

With these and other objects in view, the present invention consists in the combination and arrangement of parts as will be 15 hereinafter fully described and shown in the accompanying drawings, and particularly pointed out in the appended claims, it being understood that changes in the form, proportion, size and minor details 20 may be made without departing from the spirit or sacrificing any of the advantages of this invention.

In the drawings:—Figure 1 is a view of the improved wrench in side elevation. Fig. 2 is a view in edge elevation of the improved wrench as seen along arrow 2. Fig. 3 is a transverse sectional view of the improved wrench taken on line 3—3 of Fig. 1.

Like characters of reference indicate corresponding parts in all of the figures of the drawings.

In its preferred embodiment, the improved wrench forming the subject matter of this application comprises a shank 10 having a 35 rack composed of the teeth 11 formed along one edge and an angularly disposed rigid jaw 12 outstanding from the same edge. Between the rack and the rigid jaw is disposed a sliding jaw member 13 carrying the jaw 40 14 and retained in sliding position upon the shank by the channel member 15 having the opposite and parallel flanges 16 and 17 embracing the shank and jaw member and rigidly secured to the latter by the rivets 18. 45 A lever 19 is provided and bifurcated to form the arms 20 and 21 pivoted to the jaw member 13 near the shank as at 22, the corners of the flanges 16 and 17 being cut away as at 23 to accommodate the arms. 50 Shoulders are produced by recessing the corners of flanges 16 and 17 and constitute stops for limiting the movement of the lever upon its fulcrum. The ends of the arms 20 and 21 are flattened so as to abut

firmly against the shoulders when the lever reaches the limits of its movement.

Between the arms the detent 24 is pivoted as at 25 and having a tooth 26 held in engagement with the rack by the spring 27 secured to the lever by the rivet 28 and bearing resiliently against a shoulder 29 of the detent. Through the arms 20 and 21 is inserted the rivet 30 engaging a shoulder 31 and to limit the movement of the detent 24 and a pin 32 is inserted in the shank to 60 limit the movement of the jaw 13.

In operation the improvement is applied to the work by forcing the lever forward the shank bringing the detent 24 into engagement with the teeth 11 and owing to the inclined position of the detent the jaw 13 is forced thereby toward the jaw 12. If one movement of the lever does not move the jaw a sufficient distance the lever is released and thrown back by the spring 27 and the 70 detent drawn into engagement with another one of the teeth 11. It will be noted that the jaw member 13 and the keeper 15 are elongated to give a considerable bearing surface upon the shank 10 and that the pivot 22 80 is near the shank whereby the jaw may be moved and a great pressure exerted after the jaw 14 engages the work thereby adapting the wrench for use as a pipe or nut wrench and also as a vise to grip wire or other 85 articles.

It will be observed that the jaw member 13 and the shank 10 are of uniform transverse thickness, consequently, their sides lie in the same vertical planes and the inner 90 sides of the keeper 15 bear directly against the alined sides of the shank and the jaw member. The space between the arms 20 and 21 in a transverse direction is equal to the transverse dimension of the jaw member 95 13, consequently the said jaw member may be inserted between the said arms 20 and 21 without reducing the transverse dimension of the said jaw member and weakening the same. Also the said arms 20 and 21 are of 100 the same transverse dimension as the sides of the keeper 15 and consequently do not project beyond the sides of the said keeper and present shoulders which might interfere with the satisfactory manipulation of the 105 wrench. The parts being thus connected together a substantial implement is provided and the stress upon the jaw member is con-

veyed directly to the lever to which it is attached and from the said lever through the detent 24 to the stock 10.

Having thus described the invention, what is claimed is:-

A wrench having a stationary jaw provided with an extended shank member equipped with a plurality of teeth or serrations upon one surface thereof, a slideable keeper equipped with a jaw relatively fixed to said keeper, said keeper having cut away upper rear corners forming shoulders, and a lever member pivoted in said recesses having inner edges corresponding to the faces of the shoulders formed in said recesses and adapted to abut said faces, said lever carrying a spring pressed detent effective for engagement with

said serrations or teeth, said detent having its effective action opposed to the sliding movement of said keeper and its jaw, said lever also having a stop for engagement with said detent for its retention in initial position when said lever is lifted out of engagement with said teeth, said stationary jaw member passing through said keeper and 25 having a shank flush with the lower surface of the shank of the keeper jaw.

In testimony that I claim the foregoing as my own, I have hereto affixed my signature in the presence of two witnesses.

JAMES P. JOHNSON.
